UNITED STATES PATENT OFFICE.

MARGUERITE R. TOOLE AND LUCIUS C. TOOLE, OF INDIANAPOLIS, INDIANA.

MOTION-PICTURE-THEATER CHAIR.

1,226,416.

Specification of Letters Patent. Patented May 15, 1917.

Application filed March 16, 1916. Serial No. 84,644.

To all whom it may concern:

Be it known that we, MARGUERITE R. TOOLE and LUCIUS C. TOOLE, citizens of the United States, residing at Indianapolis, in 5 the county of Marion and State of Indiana, have invented certain new and useful Improvements in Motion-Picture-Theater Chairs; and we do hereby declare the following to be a full, clear, and exact 10 description of the invention, such as will enable others skilled in the art to which it appertains to make and use the same.

This invention relates to new and useful 15 improvements in motion picture theater chairs and the principal object of the invention is to provide a device which will permit persons occupying seats in theaters to turn so as to permit others to pass when going to or from a seat.

20 Another object of the invention is to provide a device which will prevent the chair from making a complete revolution.

Still another object of the invention is to provide a device which will permit persons 25 to pass to and from their seats in theaters without annoying other persons already in their seats and without distracting their attention from the picture projected on the screen.

30 A further object of the invention is to provide a chair which eliminates the above very annoying features as each person can remain seated by simply turning to the right or left so as to let the persons coming into or going out of their seats pass and thereby not disturb anyone and at the same time permitting the persons who are seated to keep their eyes upon the screen.

With these and other objects in view, the 40 invention consists in the novel combination and arrangement of parts which will be fully set forth in the following specification and accompanying drawings, in which:—

Figure 1 is a side view and elevation of a 45 chair constructed in accordance with this invention.

Fig. 2 is a bottom plan view thereof.

Fig. 3 is an inverted perspective view of the chair.

50 Fig. 4 is a detail view of the track, and

Fig. 5 is a detail view of the supporting arm which coöperates with the track.

Referring to the drawings numeral 1 designates the base of the chair having secured thereto and extending upwardly therefrom 55 a standard 2, the upper end of the standard is provided with an angularly extending arm 3 the upper end of which carries a roller 4 for engagement with the track on the under side of the chair which will be more 60 fully hereinafter described.

The chair consists of the seat 6 having a back 7 connected thereto and the usual arms 8. The under side of the seat has secured centrally thereof a plate 9 which is provided with a depending stem 10 for entrance 65 into an axial bore 11 in the upper end of the standard hereinbefore referred to. The track is designated by the numeral 12 and consists of a semi-circular section of channel iron or a similar material having its flanges extending downwardly and received between the flanges is the roller on the arm hereinbefore referred to. It will thus be seen that the chair will be swivelly mounted 70 on top of the standard and the opposite ends of the track are provided with suitable stops 13 for preventing the chair from swinging beyond a predetermined point.

Secured beneath the chair in any suitable 80 manner is a suitable hat support 14 which consists of a pair of parallel bars supported on upwardly extending legs which are secured to the under side of the chair as clearly illustrated in the drawings.

85 It will be apparent from the foregoing that in use the chair is assembled in the ordinary way and arranged so that it may swing to either side from the front and will be stopped after having made one fourth 90 of the revolution in either direction thereby preventing the possibility of the reversing of the chair. It will also be seen that when turned the knees of the occupant will be out of the path of the person going to or 95 coming out of his seat.

While in the foregoing there has been shown and described the preferred embodiment of this invention, it is to be understood that such changes may be made in 100

the combination and arrangement of parts as will fall within the spirit and scope of the appended claim.

What is claimed is:—

- 5 In a chair, a standard, a chair bottom swivelly connected to the standard, an arm extending upwardly and forwardly from the upper end of the standard, a roller journaled in the upper end of the arm, an arcuate trough-shaped track secured to the under side of the chair bottom, the roller operat-
- 10

ing in the track, and walls at opposite ends of the track providing stops to limit the movement of the chair bottom.

In testimony whereof we affix our signatures in presence of two witnesses.

MARGUERITE R. TOOLE.

LUCIUS C. TOOLE.
